UNITED STATES PATENT OFFICE.

ALBERT M. PIGEON, OF NORRISTOWN, PENNSYLVANIA, ASSIGNOR TO WILDMAN MFG. CO., OF NORRISTOWN, PENNSYLVANIA, A CORPORATION OF PENNSYLVANIA.

CONTROLLING MEANS FOR FABRIC CAGES FOR KNITTING MACHINES.

Application filed April 6, 1918. Serial No. 227,029.

To all whom it may concern:

Be it known that I, ALBERT M. PIGEON, a citizen of the United States, residing in Norristown, in the county of Montgomery and State of Pennsylvania, have invented 5 certain new and useful Improvements in Controlling Means for Fabric Cages for Knitting Machines, whereof the following is a specification, reference being had to the accompanying drawings.

The invention relates more particularly to knitting machines of the rotary needle cylinder type, wherein the cylinder may be rotated for circular knitting or oscillated at 15 certain intervals for knitting the heel and toe pockets of the stocking.

Prior to my invention, machines of the above type have been provided with a fabric-supporting cage which receives the knit 20 fabric, and means have also been provided for rotating the cage in unison with the needle cylinder and for suspending the rotations of the fabric supporting cage during oscillating knitting.

An object of the present invention is to provide means for disconnecting and connecting the fabric cage from its rotating mechanism which means is so controlled as to cause disconnection of the fabric cage 25 after the phase of oscillating movement of the needle cylinder begins, and reconnection just before the phase of rotative movement of the needle cylinder is resumed, so that the rotative movement of the cage itself may 30 be started with little or no shock and that strain and wear of the operative parts may thus be minimized.

In the drawings, which show by way of illustration, one embodiment of the invention, Fig. I, is a perspective view of a portion of a knitting machine having my improved fabric cage controlling means applied thereto.

Fig. II, is a view partly in side elevation 45 and partly in section showing one type of mechanism for rotating and oscillating the needle cylinder; and for shifting from rotation to oscillation, and also showing the means for controlling the movements of the fabric supporting cage.

Fig. III, is a sectional view on the line III-III, of Fig. II.

Fig. IV, is a vertical sectional view from 55 the upper part of the fabric cage through the supporting frame, and the lower part

of the needle cylinder, showing the means for connecting the fabric supporting cage to the needle cylinder.

Fig. V, is a vertical sectional view through a portion of the machine, and centrally through the main shaft.

Fig. VI, is a detail showing the operating pawl for the clutch shifting drum and controlling means therefor.

Fig. VII, is a view showing more or less 65 diagrammatically in full lines the position of the parts as the needle cylinder ends its rotating movements, and is about to begin its oscillating movements, and in dotted lines the shifting positions of the controlling cam which releases the fabric supporting 70 case from the needle cylinder.

Fig. VIII, is a detail view in side elevation of certain parts illustrated in Fig. VII, showing corresponding positions in full and 75 dotted lines.

Figs. IX and X, are views similar to Figs. VII and VIII, but showing cage released 80 from its rotating mechanism, and the parts positioned at the end of the last complete oscillation of the needle cylinder just prior to the shifting of the clutch for the beginning of the rotation of the needle cylinder, and also showing in dotted lines the shifting 85 of the controlling cam for connecting and disconnecting the fabric supporting cage with the needle cylinder.

Fig. XI, is a view showing in plan, the details of the pivotal mounting for the cam plate by which the fabric receiving cage is 90 automatically disconnected during oscillatory knitting.

I have shown my invention as applied to a knitting machine of the circular type, 95 wherein the needle cylinder is rotated for circular knitting and is oscillated at certain intervals for knitting the heel and toe parts of a stocking. As is usual in this type of machines, the oscillations of the needle cylinder are effected through reducing gearing, 100 so that the cylinder is traveling slower during oscillating movements than during its rotating movements. The fabric supporting cage is normally rotated in unison with the needle cylinder through a connecting pin, carried by the needle cylinder and coupled with the fabric supporting cage. The coupling means includes a shift- 105 able plate, which may be moved so as to disconnect the cage from said pin. My im-

provement is directed particularly to the controlling means for shifting this plate, so as to effect a connection or disconnection between the fabric supporting cage and the pin on the needle cylinder. This controlling means includes a cam plate which is shifted with the clutch lever, and which is also shifted independently of the clutch lever by the pattern controlled mechanism of the knitting machine. These shifting means are so timed and constructed as to disconnect the plate on the fabric supporting cage from the operating pin on the needle cylinder after the first oscillation of the needle cylinder begins, and preferably just at the end of the stroke of the first oscillation. This brings about the disconnection of the fabric cage from the operating means on the needle cylinder not only during the slow travel of the needle cylinder, as occurs in oscillating knitting, but at the end of the oscillation, so that the fabric cage is stopped with little or no shock whereby breakage or wear of the parts is prevented.

25 The time of the shifting of the cam plate is also so controlled as to connect the fabric supporting cage with the pin on the needle cylinder during the last oscillation of the needle cylinder, and before the clutch is shifted to cause the needle cylinder to rotate and travel at a higher speed than when oscillating. Therefore, again, I am able to connect the fabric supporting cage to this moving part of the needle cylinder with little or no shock.

30

35

Referring more in detail to the drawings, I have shown my invention as applied to a knitting machine having a supporting frame 1, in which is mounted a main shaft 2, driven by a belt wheel 3. This main shaft 2, is, as herein shown, in the form of a sleeve rotating about an inner shaft 2^a. The needle cylinder is indicated at 4, in the drawings, and is mounted to rotate on a supporting shelf 5, carried by the frame 1. At the lower end of the needle cylinder is a gear wheel 6, which is fixed to the needle cylinder. The gear wheel 6, meshes with the gear wheel 7, mounted on a short vertical shaft 8, carried by the supporting frame 1. Attached to this vertical shaft 8, is a bevel gear 9, which meshes with a bevel gear 10, loosely mounted on the inner shaft 2^a. The bevel gear 10, is carried by a sleeve 11, provided with a shifting clutch pin 12. When the clutch pin is in the position shown in Fig. V, it engages the sleeve which has been referred to as the main shaft 2. As the main shaft, therefore, rotates, the bevel gear 10, will be rotated and this through the train of means described will rotate the needle cylinder.

60

65

Mounted to rotate loosely on the inner shaft 2^a is a gear 13. This gear is adapted to be engaged by the clutch pin 12, when

it is shifted to the extreme left from the position shown in Fig. V. The gear 13, meshes with a segmental gear 14, mounted to swing about a shaft 15, as a center. This segmental gear 14, is actuated by a link 16, connected with a crank 17, on a gear 18. The gear 18, meshes with a pinion 20, attached to the main sleeve shaft 2. As this main shaft 2, rotates, the pinion 20, will rotate the gear 18, and this will oscillate the segmental gear 14, which will in turn oscillate the gear 13, and as this gear is now clutched with the bevel gear 10, the needle cylinder will be oscillated. Inasmuch as the gear 18, is large in diameter relative to the pinion 20, the travel of the needle cylinder during oscillation will be much slower than the travel of the cylinder during rotation. The clutch pin 12, is attached to a sleeve 21, and this sleeve is shifted to the right or to the left by a clutch lever 22. The clutch lever 22, is fulcrumed at 23, on the main frame, and is oscillated by a clutch shifting drum 24. This clutch shifting drum 24, as shown in Fig. I, of the drawings is provided with a cam groove 25. The lower end of the lever 22, is provided with a pin 26, which runs in this cam groove 25. The cam groove is shaped so as to operate the lever, and so as to shift the clutch pin 12, to cause it to engage directly the main sleeve shaft 2, or to engage the gear 13. The clutch shifting drum 24, is moved at times by a pattern controlled mechanism. Said drum is formed with ratchet teeth 27. Mounted on the segmental gear 14, is a pawl 28. Co-operating with this pawl 28, is a controlling plate 29, which is pivoted to an arm 30, mounted to turn about the shaft 31, on which the clutch shifting drum is carried. A spring 32, normally moves this plate 29, forward, so that the ratchet teeth 27, are covered, and the pawl 28, plays back and forth on this plate. The arm 30, is shifted by a controlling finger 33, which is adapted to engage a lug 34, formed integrally with the arm 30. This shifting finger is fixed to a shaft 35. Also carried by the shaft 35, is an arm 36, which has a nose 37, lying in the path of pattern lugs 38, carried by a pattern chain 39. This pattern chain is moved by suitable mechanism, and when the pattern lug 38, engages the nose 37, it forces the arm 36, to the right as viewed in Fig. II, and this will turn the shaft 35, moving the finger 33, so as to draw the arm 30, downward and withdraw the plate 29, from beneath the pawl 28, as shown in Fig. VI, so that the next forward movement of the pawl 28, will turn the drum. The above described means for rotating and oscillating the cylinder and for shifting the clutch lever forms no part of the present invention, per se, but is shown, described and claimed in my co-pending application Serial No. 633,938, filed June 19, 1911, 130

and issued May 14, 1918 as Patent No. 1,266,044.

Mounted directly beneath the supporting shelf 5, which carries the needle cylinder 4, 5 is a fabric supporting cage F. This fabric supporting cage is carried by a bracket arm 40, and the upper end of the fabric supporting cage is guided by the shelf 5, so that said fabric supporting cage may rotate freely 10 directly beneath the needle cylinder. Said fabric supporting cage is provided with fabric take-up rolls 41, which may be of the usual construction. Carried by the needle cylinder 4, and projecting downwardly 15 therefrom is a pin 42. Said fabric supporting cage is provided with a spring plate 43, the upper end of which is bent at right angles to the body portion of the plate, and is provided with a recess 44, of sufficient size 20 to receive the pin 42, and thus connect the fabric supporting cage to the needle cylinder, when the parts are positioned as shown in Figs. III, IV, and VII, of the drawings. The plate 43, is cut away at 45, to form a 25 cam surface so that the pin 42, riding on this cam surface, may force the plate back and snap into the recess 44. This plate 43, is bent so that its lower end (not shown) may be rigidly secured to the wall of the fabric 30 supporting cage. A pin 47, is fixed to the plate 43, near its upper end. This pin 47, extends outwardly through an opening in the side wall of the fabric supporting cage. By pressing the outer end of this pin 47, the 35 plate may be shifted, so that the upper end thereof is entirely back from the path of movement of the pin 42. When, however, the pin 47, is released, the plate 43, which is of spring metal, will at once move back in 40 a position so as to engage the pin 42.

When the parts are positioned so that the pin 42, is engaged by this plate 43, then the fabric supporting cage F, will rotate in unison with the needle cylinder.

As a means for disconnecting this plate 43, from the pin 42, I have provided a cam plate 48. This cam plate 48, is pivoted at 49, to a bracket 50, adjustably secured to the upper end of the clutch shifting lever 22, 45 by screws 51. A rod 52, is pivoted at 53, to the cam controlling plate 48. This rod 52, extends freely down through the opening in the outer end of an arm 54, which is fixed to the shaft 35, and moves up and down as the 50 arm 36, moves back and forth. An adjustable collar 55, is secured to the lower end of the rod 52. This connection as clearly shown in Fig. II, provides for a slight lost motion between the arm 54, and the rod 52, which 55 permits the stepping around of the clutch drum by the short pattern lugs on the chain. When, however, a long pattern lug on the chain 39, passes underneath the nose 37, of the arm 36, then the throw of the arm 54, is 60 sufficient to pull down the rod 52, and move the controlling cam plate 48, to the position shown in dotted lines in Figs. II, and X. This controlling cam plate 48, being mounted on the clutch lever 22, is also shifted with the clutch lever, and moved toward and 65 from the fabric supporting cage. When the clutch lever is shifted to the left, as viewed in Fig. I, then the parts are connected so as to cause the needle cylinder to oscillate, and this moves the controlling cam plate 48, close to the fabric supporting cage, so that it will engage the pin 47, provided said cam plate 48, is in raised position as shown in Fig. II. If, however, this cam plate 48, is depressed to the dotted line position shown in this figure, then the pin 47, is above the plate, and would not be engaged thereby. The cam plate is normally held in raised position by a spring 48a, see Fig. XI. The upward movement of the cam plate is limited by a stop 56.

Referring to Figs. VII, and IX, I have shown diagrammatically the pin on the needle cylinder which rotates the fabric supporting cage, the plate 43, which engages this pin, and the controlling cam plate. Let us assume that the parts are positioned so that the needle cylinder is rotating, then the clutch pin 12, is shifted to the position shown in Fig. V, and the cam plate 48, will be in the position shown in Fig. III, of the drawings, that is, out of the range of movement of the pin 47. At this time the pin on the needle cylinder engages the recess in the plate 43, and said fabric supporting cage rotates in unison with the needle cylinder. When the long cam lug 38, engages the nose 37, of the arm 36, and moves the same outward, the rod 52, will be depressed, pulling down the controlling cam 48, to the full line position shown in Fig. VIII. The pattern chain dwells at this point for one rotation of the main shaft and during this dwell, the plate 29, is retracted so as to permit the pawl 28, to engage the clutch drum and move it forward to shift the lever 22, and thus connect the parts for the oscillation of the needle cylinder. During one rotation of the shaft 70 the plate 29, is withdrawn, and during the next rotation the pawl 28, moves forward to move the clutch shifting drum for shifting the clutch. When, however, the clutch shifting drum moves forward to shift the clutch, then the pattern chain moves forward, carrying the long pattern lug out from underneath the end of the nose 37, and this releases the rod 52, so that the cam plate 48, is raised to full line position. The lever 22, as it shifts the clutch also brings this cam plate 48, into the dotted line position shown in Fig. VII, that is, into the path of movement of the pin 47. At this time when the clutch shifting drum moves to shift the clutch lever 22, the pin on the needle cylinder 75 is substantially at the point indicated in Fig. 130

VII. The movements of the needle cylinder cease, and the oscillation of the needle cylinder begins, said cylinder starting from the point indicated in this Fig. VII, and moving in a counterclockwise direction. As the cylinder moves on its first oscillating stroke, the pin 47, will engage the cam plate 48, as shown in Fig. IX, of the drawing, and this will move the plate 43, back, releasing the same from the pin on the needle cylinder. It will be noted from the above that the releasing of the fabric supporting cage from the pin 42, does not occur until the needle cylinder begins its oscillating movement, and as a matter of fact is timed to occur just as the cylinder completes an oscillation, and is at its reverse point, so that movement of the fabric supporting cage is stopped, or substantially stopped, at the moment when the same is disconnected from the needle cylinder. This disconnecting of the fabric supporting cage from the needle cylinder while said needle cylinder is traveling slowly, or is stationary, avoids shock and the consequent wear and breakage. When the machine reaches a point wherein it passes automatically from oscillating knitting to round and round knitting, the fabric supporting cage is again connected up to the needle cylinder, but this connection of the fabric supporting cage to the needle cylinder occurs before the needle cylinder is clutched to the operating gears for rotation. The pin 47, is held pressed inwardly by the cam plate 48, as long as said cam plate remains in the full line position shown in Fig. IX. The long pattern lug 38, moves the arm 36, and then dwells as above noted. It is this motion of the arm 36, which shifts the rod 52, and moves the cam controlling plate 48, to the dotted line position shown in Figs. II, and X. The shifting of this cam plate 48, to the dotted line position releases the pin 47, and this occurs before the clutch lever 22, is shifted to cause the cylinder to rotate, for the reason that it is during the next oscillation of the segmental gear that the clutch controlling drum is moved to shift the clutch. The needle cylinder is traveling on its last oscillation in a counterclockwise direction, when the plate 43, is released, and the pin 42, riding up on the cam surface 45, will snap into the recess 44. The needle cylinder then moves in a clockwise direction, and the clutch is shifted at a point indicated in Fig. IX, of the drawings, so that the cylinder then at once begins its rotating motion. In other words, the pin 42, is connected with the fabric supporting cage during the actual oscillating movement, or at the end of an oscillating stroke of the cylinder, and before it begins the relatively rapid travel characteristic of the rotative phase of operation, and, therefore, this connecting of the fabric supporting cage to the needle cyl-

inder is brought about with little or no shock and consequent breakage or wear of the parts.

It is understood of course that the mechanism shown in detail in the drawings may be modified and the time varied, the essential feature being the connecting of the fabric supporting cage in operative relation to the needle cylinder, and its disconnection therefrom, at times when the needle cylinder is on its phase of oscillating movement and, therefore, traveling slowly, whereby the desirable results above stated are attained.

I am aware that it has heretofore been suggested that the fabric cage or web receiver, or parts carrying the same be disconnected from the cylinder during reciprocating movements of the latter; but, in the mechanism suggested for accomplishing this purpose the mode of operation is such that the disconnection takes place while the machine or cylinder and the fabric cage are both at rest. The present invention is in contrast with this mode of operation in that I contemplate effecting the connection or disconnection while the cylinder and fabric cage are both in motion and traveling coincidentally and always during an oscillating phase and never during a rotating phase.

In addition to the advantage previously pointed out of avoiding shock to and wear of the parts it will be remembered that when changing from rotary to reciprocating knitting the cage is carried back over the first period of reciprocation before the disconnection is effected, and the disconnection then takes place just before the end of this period. As a result the momentum of the cage, subsequent to disconnection carries it to the point where the pin 47 engages the stop 56 thus bringing the cage to rest. The point of arrest of the cage will thus be always the same. If the disconnection were not made while the cylinder and cage were in motion but instead was timed to take place exactly at the moment when the pin engaged the stop a shock to the parts could not be avoided. With respect to the point in the operation of the machine when the change is made from reciprocating to rotary knitting the connection between the cylinder and cage is effected while the cylinder is in motion and passing from a reciprocating phase into continuous rotary motion, without stopping the cylinder. This results in an advantage in that no time is lost in bringing the cylinder to complete rest. There is little shock incidental to setting the cage in motion at this period since the cylinder is slowed down at the end of its last reciprocation and while slowing down the connection is made without entirely stopping the cylinder, the latter, immediately after the connection is made picking up speed for its rotary motion.

- Having thus described my invention, I claim:
1. In a knitting machine, the combination of an alternatively rotating and oscillating needle cylinder; a fabric-receiving cage; means for actuating said needle cylinder and said cage in unison; and means for automatically disconnecting said cage after the oscillating phase of the needle cylinder has begun, so as to suspend movement thereof in said oscillating phase. 10
  2. In a knitting machine, the combination of an alternatively rotating and oscillating needle cylinder; a fabric-receiving cage; means for actuating said needle cylinder and said cage in unison; and means for automatically disconnecting said cage to suspend movement thereof in the oscillating phase of the needle cylinder, and for reconnecting it for the rotary phase of said needle cylinder before the beginning of said rotary phase. 15
  3. In a knitting machine, the combination of an alternatively rotating and oscillating needle cylinder travelling at a lower maximum rate in its oscillating phase than normally in its rotating phase; a fabric-receiving cage; means for actuating said needle cylinder and said cage in unison; and means for automatically disconnecting and reconnecting said cage, to suspend movement thereof, both during the phase of slow movement of the needle cylinder. 25
  4. In a knitting machine, the combination of an alternatively rotating and oscillating needle cylinder; a fabric-receiving cage; means for actuating said needle cylinder and said cage in unison; and means for automatically disconnecting said cage, to suspend movement thereof in the oscillating phase of the needle cylinder, when the cage is substantially at rest just after the beginning of said oscillating phase. 30
  5. In a knitting machine, the combination of an alternatively rotating and oscillating needle cylinder; a fabric-receiving cage; means for actuating said needle cylinder and said cage in unison; and means for automatically disconnecting said cage to suspend movement thereof in the oscillating phase of the needle cylinder, and reconnecting it for the rotary phase of said cylinder when the cage is substantially at rest before the resumption of said rotary phase. 45
  6. In a knitting machine, the combination of an alternatively rotating and oscillating needle cylinder; a fabric-receiving cage; means for actuating said needle cylinder and said cage in unison; and means for automatically disconnecting said cage, to suspend movement thereof in the oscillating phase of the needle cylinder, when the cage is substantially at rest just after the beginning of said oscillating phase, and for reconnecting said cage for the rotary phase 55
  - of said needle cylinder when the cage is substantially at rest just before the resumption of said rotary phase. 60
  7. In a knitting machine, the combination with an alternatively rotating and oscillating needle cylinder, a fabric-receiving cage, and means for actuating said needle cylinder and cage in unison; of a member shiftable one way or another to change the motion of said needle cylinder from rotary to oscillatory and vice versa; and means carried by said member for disconnecting and reconnecting said cage to suspend movement thereof in the oscillating phase of said needle cylinder. 70 75
  8. In a knitting machine, the combination with an alternatively rotating and oscillating needle cylinder, a fabric-receiving cage, means for actuating said needle cylinder and said cage in unison, and a pattern mechanism; of means for changing the motion of said needle cylinder from rotary to oscillatory and vice-versa controlled by said pattern mechanism; means actuated by said motion-changing means for disconnecting and reconnecting said cage, to suspend movement thereof in the oscillating phase of said needle cylinder; and means for controlling the action of said disconnecting and reconnecting means independently actuated by said pattern-mechanism. 80 85 90
  9. In a knitting machine, the combination with an alternatively rotating and oscillating needle cylinder, a fabric-receiving cage, means for actuating said needle cylinder and said cage in unison, and a pattern mechanism; of means for changing the motion of said needle cylinder from rotary to oscillatory and vice-versa actuated by said pattern mechanism; means for disconnecting and reconnecting said cage, to suspend movement thereof in the oscillating phase of said needle cylinder; and means actuated by said pattern-mechanism independently and in advance of said motion-changing means for controlling the action of said disconnecting and reconnecting means. 100 105 110
  10. In a knitting machine, the combination of an alternatively rotating and oscillating needle cylinder; a fabric-receiving cage; means for actuating said needle cylinder and said cage in unison, including an automatic latch mechanism for connecting the cage with its driving element; and cam means adjacent the path of movement of said latch mechanism cooperating therewith to cause disconnection and reconnection thereof, and thereby temporarily suspend movement of the cage. 115 120
  11. In a knitting machine, the combination of a needle cylinder; means for rotating and for oscillating said needle cylinder, including a clutch, a clutch lever for shifting said clutch, and pattern control mechanism for shifting said lever; a fabric-sup- 125 130

- porting cage; means for rotating said fabric-supporting cage by operative connection with the needle cylinder; means for disconnecting said cage from the needle cylinder; 5 and means, operated by the pattern control mechanism prior to the shifting of the clutch to effect rotation of the needle cylinder, for connecting the fabric-supporting cage to the needle cylinder.
- 10 12. In a knitting machine, the combination of a needle cylinder; means for rotating and for oscillating said needle cylinder, including a clutch, a clutch lever for shifting said clutch, and pattern control mechanism 15 for shifting said lever; a fabric-supporting cage; means for rotating said fabric-supporting cage by operative connection with the needle cylinder; means, operated by said clutch shifting lever, for disconnecting said 20 cage from said cylinder; and means, operated by said pattern control mechanism prior to the movement of the clutch shifting lever to effect rotation of the cylinder, to permit the connection of the cage 25 to its rotating means.
13. In a knitting machine, the combination of a needle cylinder; means for rotating and for oscillating said needle cylinder, including a clutch, a clutch lever for 30 shifting said clutch, and pattern control mechanism for shifting said lever; a fabric-supporting cage; means for rotating said fabric-supporting cage by operative connection with the needle cylinder; a cam 35 plate shiftable in one direction by said clutch shifting lever and in another direction by said pattern control mechanism; and devices co-operative with said cam plate to disconnect the cage from its rotating 40 means, and to permit said cage to be connected to its rotating means.
14. In a knitting machine, the combination of a needle cylinder; means for rotating and for oscillating said needle cylinder, 45 including a clutch, a clutch lever for shifting said clutch, and pattern control mechanism for shifting said lever; a fabric-supporting cage; means for rotating said fabric supporting cage by operative connection 50 with the needle cylinder; a cam plate pivotally supported by said clutch shifting lever; means operated by the pattern control mechanism for moving said cam plate vertically, said cam plate operating to disconnect the cage from its rotating means when 55 in raised position and shifted by the clutch lever to a point adjacent the cage, said cam plate also operating, when depressed by the pattern control mechanism, to permit the 60 cage to be connected to its rotating means.
15. In a knitting machine, the combination of a needle cylinder; means for rotating and for oscillating said needle cylinder, in- 65 cluding a clutch, a clutch lever for shifting said clutch, and pattern control mechanism for shifting said lever; a fabric-supporting cage; means for rotating said fabric-supporting cage by operative connection with the needle cylinder; a cam plate for connecting said cage to its rotating mechanism and disconnecting it therefrom, and devices for operating said cam plate 70 from the pattern control mechanism, in depressing the latter to effect the connection of the cage to its rotating means prior to 75 the operation of the clutch lever to cause rotation of the cylinder.
16. In a knitting machine, the combination of a needle cylinder; means for rotating and for oscillating said cylinder, including a clutch; a clutch lever for shifting said clutch; a depending pin carried by said cylinder; a fabric-supporting cage beneath said cylinder; a spring plate having a laterally projecting end formed with a recess 80 adapted to engage said pin for connecting said cage to the said cylinder; a device for shifting said plate for disconnecting the same from said cylinder; and a controlling cam plate for operating said device, said 85 cam plate being moved by the clutch shifting lever into position for engaging said device to release the cage from the cylinder such engagement occurring while said cylinder is on its phase of oscillating movement.
17. In a knitting machine, the combination of a needle cylinder; means for rotating and for oscillating said cylinder, including a clutch; a clutch lever for shifting 90 said clutch; a depending pin carried by said cylinder; a fabric-supporting cage beneath said cylinder; a spring plate having a laterally projecting end formed with a recess adapted to engage said pin for connecting said cage to the said cylinder; a device for shifting said plate for disconnecting same from said cylinder; a controlling cam plate for operating said device, said 95 cam plate being moved by the clutch shifting lever into position for engaging said device to release the cage from the cylinder while said cylinder is on its phase of oscillating movement.
18. In a knitting machine, the combination of a needle cylinder; means for rotating and for oscillating said cylinder, including a clutch; a clutch lever for shifting 100 said clutch; a depending pin carried by said cylinder; a fabric-supporting cage beneath said cylinder; a spring plate having a laterally projecting end formed with a recess adapted to engage said pin for connecting said cage to the said cylinder; a device for shifting said plate for disconnecting same from said cylinder; a controlling cam plate for operating said device, said 105 cam plate being moved by the clutch shifting lever into position for engaging said device to release the cage from the cylinder while said cylinder is on its phase of oscillating movements; and pattern controlling means for moving said controlling cam plate for releasing said device to permit the cage to be connected with the cylinder while said cylinder is on its phase of oscillating movement.
19. In testimony whereof I have hereunto set 110 my hand at Philadelphia, Pennsylvania, this third day of April, 1918.
